Primary Examiner — Eric Goodman*Assistant Examiner* — Sloan Rozin(74) *Attorney, Agent, or Firm* — NSIP Law(57) **CLAIM**

We claim the ornamental design for a display screen or portion thereof with icon, as shown and described.

DESCRIPTION

FIG. 1 is a front view of a display screen or portion thereof with icon showing our new design; and, FIG. 2 is another front view thereof.

The broken line showing of the display screen in FIG. 2 is for environmental purposes only and forms no part of the claimed design.

The dot dash lines in the figures represent an unclaimed boundary line and form no part of the claimed design.
